UNITED STATES PATENT OFFICE.

HORACE E. RICE, OF PHILADELPHIA, PENNSYLVANIA; KATHLEEN F. RICE ADMINISTRATRIX OF SAID HORACE E. RICE, DECEASED.

IGNITION APPARATUS.

Application filed November 12, 1920. Serial No. 423,633.

To all whom it may concern:

Be it known that I, HORACE E. RICE, a citizen of the United States, residing in the city and county of Philadelphia, State 5 of Pennsylvania, have invented new and useful Improvements in Ignition Apparatus, of which the following is a specification.

My invention relates to ignition apparatus for internal combustion engines, especially 10 when comprising a large number of cylinders.

It is the object of my invention, though it may be otherwise availed of, to provide ignition for an engine comprising a great 15 number of cylinders, as eight, twelve, or more, especially when the cylinders are disposed in groups at an angle to each other, as in twin fours, twin sixes, etc., with the angle between the groups differing from 20 the usual angle between groups and necessitating ignition sparks at non-uniform intervals.

For example, my system is utilizable with a twin six engine in which one group of 25 six cylinders is disposed at an angle of 45 degrees with the second group of six cylinders, as for example, in the Liberty motor employed upon aeroplanes in the late war.

30 My invention resides in ignition apparatus for the purposes above described, or for any other purpose where suitable or available, comprising a plurality of timer or interrupter structures whose cam driven 35 or cam controlled members are actuated or controlled by a cam whose active faces or points are uniformly spaced around the circumference of the cam, while the interrupter or timer structures are unsymmetrically 40 positioned with respect to the cam to effect ignition sparks recurring at non-uniform intervals.

45 My invention resides in further features of structure and combination hereinafter described and claimed.

For an understanding of my invention and for an illustration of one of the various forms it may take, reference is to be had to the accompanying drawings, in which:

50 Fig. 1 is a diagrammatic view of the interrupter or timer structure and associated circuits.

Fig. 2. is a diagrammatic view illustrating motor cylinders or groups of cylinders disposed at an angle with respect to each other.

Fig. 3 is a plan view of part of my apparatus.

Fig. 4 is a vertical sectional view, some parts in elevation, taken on the line 4—4 60 of Fig. 3, and through structure additional to that shown in Fig. 3.

Fig. 5 is a plan view of part of the structure shown in Fig. 4.

Referring to Fig. 1, alternate spark plugs 65 p are those of the six cylinders or one group, and are connected to the stationary distributor terminals t ; while the plugs p^1 , connected to the stationary distributor terminals t^1 , are those of another group of six 70 cylinders, the two groups forming a twin six engine.

Ordinarily the two groups are so arranged that between their cylinder axes there is an angle of 60 degrees. In some cases, however, as indicated in Fig. 2, the two cylinder groups C and C^1 are so disposed that the angle between the cylinder axes is 45 degrees. Such is the case in the Liberty twin six motor hereinbefore referred to. 80

In consequence, when cylinder firing takes place alternately in the different groups, the angular distance between a distributor terminal t and the succeeding terminal t^1 is 22½ degrees, while the angle between each 85 distributor terminal t^1 and the succeeding terminal t is 37½ degrees, as indicated in Fig. 1, when the rotary distributor arm D rotates at half engine speed.

The distributor arm D is connected to one 90 terminal of the high tension secondary winding S of an induction coil I whose primary P is connected in the primary circuit extending from the ground or frame G through battery B , switch s , binding post a , the aforesaid primary coil P , binding post b to the interrupters or timers A and B , both shunted by the condenser K , to ground or frame G .

The interrupter mechanisms A and B are 100 shown to be similar in structure, though such similarity is not essential. In the example illustrated they are of the open circuit type, an example of which is described

in Kent's Patent No. 1,246,818, though it will be understood that my invention comprehends also the employment of closed circuit interrupters such as illustrated, for example, in Kent's Patent No. 1,289,036. As illustrated, each interrupter comprises the stationary interrupter contact 1 which is momentarily engaged by the cooperating moving contact 2 carried by the yieldingly mounted member 3, with which is associated the hooked member 4 actuated by the intermediate or hammer member 5, pivoted at 6 and in turn actuated by the member or lifter 7 controlled by spring 8 and actuated by cam 9, rotated by and at half speed with respect to the main crank shaft of the motor.

The cam 9 has its control teeth, points or faces, uniformly spaced circumferentially, whereby for each sixth of a revolution of the cam 9, the interrupter contacts 1 and 2 of one of the interrupters engage and separate and produce a spark. Similarly, in the other interrupter the contacts 1 and 2 engage and separate for each sixth revolution of the cam 9, similarly producing a spark, but the sparks produced by one interrupter, as A, alternate with those produced by the other interrupter, as B. In other words, the interrupter A may produce sparks for all the cylinders of one group, while B produces the sparks for all the cylinders of the other group. While the sparks in the two groups alternate, they do not occur at uniform intervals, as above stated. To ensure that they occur at the proper intervals or instants the interrupters A and B are unsymmetrically placed as regards angular position about the cam 9, whereby the interrupter A is operated, and upon further rotation of $22\frac{1}{2}$ degrees by cam 9 the interrupter B is actuated; thereafter the cam 9 rotates $37\frac{1}{2}$ degrees further before again actuating the interrupter A. The interrupters A and B are not opposite each other or displaced by 180 degrees, but by 180 degrees less $22\frac{1}{2}$ degrees.

Accordingly, notwithstanding the fact that the cam points are uniformly spaced, ignition sparks are produced at unequal intervals; and further, notwithstanding the fact that the cam has a certain number of points, six in the example illustrated, there are produced for each revolution of the cam twice as many sparks as there are cam points.

It will be understood, however, that in case sparking at uniform intervals is desired, the same cam and interrupters may be employed. Again assuming a twin six motor, but with the groups at 60 degrees with respect to each other, the interrupters would be placed, for example, 180 degrees less 30 degrees, or 150 degrees from each other. In any event, after actuating one

interrupter the cam will be rotated 30 degrees and then operate the other, and so on in succession.

As an example of a structure embodying my invention, reference is now had to Figs. 3 to 5 inclusive, wherein 10 is a base or support upon which is the flange 11 having slots 12 through which may extend bolts or other means for fastening the base 10 upon the framework of the engine or other suitable support, the slots 11 allowing circumferential adjustment of the base 10 before finally securing it. At its one end the base 10 has the inwardly turned flange 12 in which are the circumferentially extending slots 13, Fig. 5, through which extend screws or bolts 14, each carrying on its lower end the nut 15 between which and the under side of the flange 12 is disposed a spring 16 surrounding the bolt 14, whereby the casing 17, having flange 18 bearing upon flange 12, is resiliently held to the base member 10, the slots 13 allowing rotation of the casing 17 through suitable angle for purposes of advancing or retarding ignition. Upon the bottom of the casing 17 is the bearing sleeve 19 within which is the bearing bushing 20 in which rotates the shaft 21 carrying a collar 22 and beneath the collar the transversely extending bar or laminated key 23, which detachably connects with a shaft driven by the engine or motor at half the speed of the main crank shaft of the motor, assuming the latter to be of the type employing four strokes per cycle.

Within the casing 17 there is secured to the shaft 21 the governor plate 24, to which are secured springs 25 connected to governor arms 26 pivoted to the plate 24 at 27 and actuating under the influence of centrifugal force the cam carrying plate 28 to move the same angularly with respect to the shaft 21. Secured to the plate 28 is the cam member 9 through which freely extends the distributor shaft 29 concentric with and secured to or integral with the shaft 21.

Covering the casing 17 is the metal plate 30, upon which are mounted the interrupters A and B, a lug or lever arm 30^a serving to rotate the plate 30 and the interrupters with respect to the cam 9 for advance or retardation of ignition. Through the plate 30 extends the aforesaid cam member 9 and through it the distributor shaft 29, whose upper end terminates in the semi-circular portion 31 which with part of the circumferentially complete shaft 29 extends into the detachable or removable distributor block 32 of insulating material, having the central boss 33 extending through an aperture in the metallic distributor member D having the rearwardly extending balancing portion d. The distributor D is secured to block 32 by screw 34, threaded into an in-

sert 35 molded in the block 32. Secured under the head of the screw 34 in contact with the distributor D is the bowed spring contact 36 whose free end engages the part 5 *d* of the distributor.

The member 37 of insulating material, preferably molded, forms a housing for the distributor and for the interrupter mechanisms A and B, whose parts are mounted 10 within the casing 37 on the upper face of the plate 30, in cooperative relation with the cam 9, as hereinbefore described.

In the bottoms of depressions 38 in the upper edge of the casing member 37 and 15 extending to the inner wall or face thereof are secured the inwardly projecting distributor terminals *t* and *t'* hereinbefore referred to, the outer end of the distributor D passing closely adjacent the inner ends of 20 these distributor terminals, whereby the high tension energy from the secondary S leaps the small gaps between the distributor D and the terminals *t* and *t'* in passage to the spark plugs. The connections from the 25 spark plugs to the distributor terminals extend into the apertures 39 terminating in smaller apertures through which the conductors themselves extend into contact with the distributor terminals, to which they may 30 be soldered or otherwise secured. Upon the upper edge of the casing member 37 is disposed the rubber or other gasket 40, and upon it rests the lower flange 41 of the housing or casing 42, preferably of insulating 35 material, within which is housed the induction coil I which, if suitable or desirable, may be molded directly in insulating material forming the casing 42. Forming the bottom of the casing 42 is the plate 43, preferably of insulating material, carrying the axial contact 44, with which engages the aforementioned distributor contact 36 and connected to yielding contact 45 adapted to 40 engage and contact with the terminal 46 constituting one terminal, as 47; Fig. 1, of the high tension secondary S of the induction coil I, the other terminal of the secondary S being connected to the primary P whose terminals connect, as previously 45 stated, to the binding posts *a* and *b*, comprised in part of the bolts 48 and 49 serving to clamp the casing 42 to the casing 37. Connection to switch *s*, Fig. 1, is made by conductor held under binding post *a*, Fig. 50 50. 4. The bolt 49 serves also to form electrical connection between one terminal of the primary P of the induction coil and the conductor 50, which is clamped by screw 51 in contact with the condenser housing plate 52 secured upon the top face of the plate 30 by screws 53, the plate 52 being, however, insulated from plate 30, which latter is grounded or connected to the frame by metallic communication through casings 17 55 and 10 and flange 11, whereby the movable

contact 2 of interrupter A and stationary contact 1 of interrupter B, secured to and connecting with the plate 30, are grounded.

Between the plate 52 and plate 30 is held the aforementioned condenser K, whose one 70 terminal connects with the plate 30 and whose other terminal electrically connects with the insulated cover plate 52. The stationary contact 1 of the interrupter A is supported by the lug 54 upon the condenser cover plate 52; similarly, the movable contact 2 of the interrupter B connects through its resilient support 3 with the condenser cover 52, upon which said member 3 is secured and with which it electrically 75 connects. Accordingly the condenser cover 52 and one terminal of the condenser, together with the stationary contact of one interrupter and the movable contact of the other interrupter, are connected through 80 conductor 50 and binding post *b* with one terminal of a primary P of the induction coil I.

While, as hereinbefore stated, other types 90 of interrupters than the open circuit type disclosed may be employed, there is a preference for the open circuit type, particularly when of the structure herein disclosed, in that back firing or premature ignition of the motor cannot occur, and in that auxiliary apparatus for preventing back firing need 95 not be provided. In the example illustrated, rotation of the cam 9 in direction opposite to that indicated by the arrow, for a part of a revolution or more, will not, because of the structure and relation of the members 5 and 7, cause engagement and separation of the interrupter contacts essential to production of igniting sparks.

Certain of the subject matter herein disclosed is claimed in application Serial No. 658,247, filed August 20, 1923.

What I claim is:

1. The combination with a multi-cylinder internal combustion motor producing torque impulses succeeding each other at unequal intervals, of ignition apparatus therefor comprising cam structure actuated by said motor, a plurality of interrupter mechanisms controlled by said cam structure having elements so positioned with respect to said cam structure that they are dissimultaneously controlled thereby at unequal intervals, and a single distributor mechanism comprising a single distributor terminal 110 rotatable in unison with said cam structure and co-acting stationary terminals circumferentially spaced at unequal intervals.

2. Ignition apparatus comprising a support, a plurality of dissimultaneously operated interrupter mechanisms each comprising stationary and movable contacts, a contact of each interrupter mechanism carried on said support, a condenser common to said interrupter mechanisms, and a plate confin- 125

ing said condenser upon said support, the other contacts of said interrupter mechanisms being supported on said plate.

3. Ignition apparatus comprising a support of conducting material, a plurality of dissimultaneously operated interrupter mechanisms each comprising stationary and movable contacts, a contact of each interrupter mechanism carried on said support, 10 a condenser common to said interrupter mechanisms, and a plate confining said condenser upon said support and insulated from said support, the other contacts of said interrupter mechanisms being supported on said plate.

4. Ignition apparatus comprising a support, a plurality of interrupter mechanisms each comprising stationary and movable contacts, the stationary contact of one of 20 said interrupter mechanisms and the movable contact of another carried upon said support, a condenser common to said interrupter mechanisms, and a plate confining said condenser upon said support, the other contacts of said interrupter mechanisms being supported on said plate.

5. Ignition apparatus for producing ignition for a multi-cylinder internal combustion motor at unequal intervals comprising 30 cam structure actuated by the motor, a plurality of interrupter mechanisms controlled by said cam structure having elements so positioned with respect to said cam structure that they are dissimultaneously controlled thereby at unequal intervals, a single induction coil controlled dissimultaneously at unequal intervals by said interrupter mechanisms, and means for delivering ignition energy from the secondary of 40 said induction coil to the motor cylinders in succession.

6. Ignition apparatus for producing ignition for a multi-cylinder internal combustion motor at unequal intervals comprising 45 cam structure actuated by the motor, a plurality of interrupter mechanisms controlled by said cam structure having elements so positioned with respect to said cam structure that they are dissimultaneously controlled thereby at unequal intervals, a single induction coil controlled dissimultaneously at unequal intervals by said interrupter mechanisms, and a single distributor mechanism comprising a rotatable distributor and 50 co-acting stationary terminals, at least one for each motor cylinder, said stationary terminals being circumferentially spaced at unequal intervals corresponding with the intervals of control of said interrupter mechanisms by said cam structure.

7. Ignition apparatus for producing ignition for a multi-cylinder internal combustion motor at unequal intervals comprising 55 cam structure actuated by said motor, a plurality of interrupter mechanisms controlled

by said cam structure having elements so positioned with respect to said cam structure that they are dissimultaneously controlled thereby at unequal intervals, an induction coil, said interrupter mechanisms 70 connected in different branches of the primary circuit of said induction coil to break said primary circuit dissimultaneously at unequal intervals, and means for delivering ignition energy from the secondary of said induction coil to the motor cylinders in succession. 75

8. Ignition apparatus for producing ignition for a multi-cylinder internal combustion motor at unequal intervals comprising 80 cam structure actuated by the motor, a plurality of interrupter mechanisms controlled by said cam structure having elements so positioned with respect to said cam structure that they are dissimultaneously controlled thereby at unequal intervals, an induction coil, said interrupter mechanisms connected in different branches of the primary circuit of said induction coil to break said primary circuit dissimultaneously at 85 unequal intervals, and a single distributor mechanism comprising a rotatable distributor and co-acting stationary terminals, at least one for each motor cylinder, said stationary terminals being circumferentially spaced at unequal intervals corresponding with the intervals of control of said interrupter mechanisms by said cam structure. 90

9. Ignition apparatus for producing ignition for a multi-cylinder internal combustion motor at unequal intervals comprising 100 cam structure having uniformly spaced control faces in number one-half the number of cylinders of said motor, a plurality of interrupter mechanisms controlled by said cam structure having elements so positioned that they are dissimultaneously controlled by said cam structure at unequal intervals, a single induction coil controlled dissimultaneously at unequal intervals by said interrupter mechanisms, and mean for delivering ignition energy from the secondary of 105 said induction coil to the motor cylinders in succession. 110

10. Ignition apparatus for producing 115 ignition for a multi-cylinder internal combustion motor at unequal intervals comprising cam structure having uniformly spaced control faces in number one-half the number of cylinders of said motor, a plurality of interrupter mechanisms controlled by said cam structure having elements so positioned that they are dissimultaneously controlled by said cam structure at unequal intervals, a single induction coil controlled 120 dissimultaneously at unequal intervals by said interrupter mechanisms, and a single distributor mechanism comprising a rotatable distributor and co-acting stationary terminals, at least one for each motor cylinder. 125

inder, said stationary terminals being circumferentially spaced at unequal intervals corresponding with the intervals of control of said interrupter mechanisms by said cam structure.

11. Ignition apparatus for producing ignition for a multi-cylinder internal combustion motor comprising cam structure actuated by the motor, a plurality of interrupter mechanisms controlled dissimultaneously by said cam structure and each comprising a stationary and a movable contact, a condenser common to said interrupter mechanisms and shunting them, an insulated conducting member covering said condenser, and connected to one terminal of said condenser, and one of the contacts of each of said interrupter mechanisms carried by and electrically connected to said conducting member.

12. Ignition apparatus for a multi-cylinder internal combustion motor comprising a cam driven by said motor, a plurality of open circuit interrupter mechanisms controlled dissimultaneously by said cam, a single stationary induction coil whose primary circuit is controlled dissimultaneously by said interrupter mechanisms, a battery in said circuit, and a single distributor distributing high tension current from the secondary of said induction coil to the cylinders of said motor.

13. Ignition apparatus for a multi-cylinder internal combustion motor for producing ignition at unequal intervals comprising a cam driven by said motor, a plurality of open circuit interrupter mechanisms controlled dissimultaneously and at unequal intervals by said cam, a single induction coil, a battery in the primary circuit of said induction coil, said interrupter mechanisms controlling said primary circuit dissimultaneously at unequal intervals, and a single distributor delivering high tension ignition energy from the secondary of said induction coil at unequal intervals to the cylinders of said motor.

14. The combination with a multi-cylinder internal combustion motor producing torque impulses succeeding each other at unequal intervals, of ignition apparatus therefor comprising cam structure actuated by said motor, a single induction coil, a plurality of interrupter mechanisms controlled by said cam structure at unequal intervals and separately controlling said induction coil, and a single distributor mechanism comprising a distributor terminal rotatable in unison with said cam structure and co-acting stationary terminals circumferentially spaced at unequal intervals.

15. The combination with a multi-cylinder internal combustion motor producing torque impulses succeeding each other at unequal intervals, of ignition apparatus therefor comprising cam structure actuated by said motor, a single induction coil, 50 a plurality of interrupter mechanisms controlled by said cam structure at unequal intervals and separately controlling said induction coil, and a single distributor mechanism comprising a distributor terminal rotatable in unison with said cam structure and co-acting stationary terminals circumferentially spaced at unequal intervals.

In testimony whereof I have hereunto affixed my signature this 11th day of November, 1920.

HORACE E. RICE.
